LOCK CONSTRUCTION

John B. Humphries, Stamford, Conn., assignor to The Excelsior Hardware Company, Stamford, Conn.

Filed June 26, 1957, Ser. No. 668,238

7 Claims. (Cl. 292—99)

This invention relates to a luggage latch construction or the like. More particularly, the invention is concerned with a latch suitably accommodated on a substantially flat surface of a suitcase or the like and having its releasing mechanism disposed substantially flush with the surface of the suitcase on which it is mounted.

An object of this invention is to provide a latch construction which will be pleasing in appearance and simple in construction. Another object of this invention is to provide a latch construction of the above character in which the various parts are free from complexity and may be inexpensively manufactured and assembled. Another object of this invention is to provide a latch construction of the above character in which the assembly may be mounted in operating position on a suitcase with great ease, thus reducing the manufacturing costs. Another object of this invention is to provide a latch construction of the above character in which the releasing mechanism is pleasing in appearance because of its simplicity and the fact that it may be mounted flush with the exposed or front surface of the suitcase. Another object of this invention is to provide a latch construction of the above character which will greatly facilitate the opening and closing of the suitcase. Other objects will be in part obvious and in part pointed out hereinafter.

The invention accordingly comprises the features of construction, combinations of elements, and arrangements of parts, which will be exemplified in the construction hereinafter set forth, and the scope of the invention will be indicated in the claims.

In the accompanying drawings in which is shown one of the various possible embodiments of this invention,

Figure 1 is a fragmentary perspective view of the front corner section of a suitcase with my latch construction mounted therein,

Figure 2 is a vertical sectional view of the latch construction taken along the lines 2—2 of Figure 1,

Figure 3 is a horizontal sectional view taken along the line 3—3 of Figures 2 and 7,

Figure 4 is a horizontal sectional view taken along the line 4—4 of Figures 2 and 7 showing the latch construction in the closed or locked position,

Figure 5 is a horizontal sectional view taken along the line 5—5 of Figure 7 showing the latch construction in the open or release position,

Figure 6 is a vertical sectional view of the latch mechanism taken along the line 6—6 of Figure 3,

Figure 7 is a vertical sectional view taken along the line 7—7 of Figure 3 with the parts in the closed or locking position,

Figure 8 is a vertical sectional view similar to Figure 7 with the parts in the open or release position, and

Figure 9 is an exploded perspective view showing the four sets of assemblies comprising the lock construction to be described and depicting their interrelation.

Similar reference characters refer to similar parts throughout the several views of the drawings.

Generally speaking, the latch construction comprises

2

a base plate generally indicated at 10 (Figures 1, 2 and 9) having pivotally mounted therein a release lever generally indicated at 12 (Figures 1, 2, 3 and 9), the face plate being mounted in the usual position on the front side of a suitcase generally indicated at 14 (Figure 1). As will be understood from a consideration of Figures 1, 2 and 9, a casing plate generally indicated at 16 is mounted on the rear or the side wall of the suitcase preferably in a suitable recess formed therefor (not shown), and this casing plate houses the latching mechanism adapted to co-act with a hook 18 (Figure 1) extending from the bottom edge of the usual hinged top 20 of the suitcase. Thus there is an opening 22 in the top of casing plate 16 (Figures 1 and 9) and immediately therebeneath there is a sliding U-shaped bar generally indicated at 24 (Figures 7, 8 and 9), a sliding latch bar generally indicated at 26 and a latch member generally indicated at 28 pivotally supported thereon. Latch member 28 is urged upwardly by a spring 30, and latch member 28 is pivoted in a counterclockwise direction (Figures 7, 8 and 9) by a spring 32.

As best seen in Figures 3 and 7, when the case is closed the hook 18 presses bar 24 to its lower-most position, and this pivots latch member 28 to an interfitting or latching position therewith to lock the case in the closed position. As can be seen in Figures 4 and 7, a lug 34 extends inwardly from release lever 12, and when the parts are in the locked or closed position, this lug fits over an extension 26a of sliding latch bar 26 thus holding the parts in the latched or locked position. To release the latching mechanism, it is merely necessary to press the release lever 12 to pivot it in a clockwise direction as viewed and indicated in Figure 5 which moves lug 34 away from extension 26a thereby permitting spring 30 to urge bar 24 and latch bar 26 upwardly; this pivots latch member 28 in a clockwise direction (Figures 7 and 8) to the release position as shown in Figure 8.

As can be seen in Figures 1, 2 and 3, face plate 10 includes a flange 36 resting against the front of the case and inwardly extending walls 38, 40 (Figure 3), 42 and 44 (Figure 2). There is a rear closure plate 46 interfitting with these walls (Figure 2) and suitably secured to face plate 10 by any suitable means. As can be seen in Figures 2 and 3, release lever 12 has a pair of pins 48 and 50 extending from the opposite sides thereof and fitting into suitable holes formed in walls 42 and 44 (Figure 2). The left portion 12a of release lever 12, as seen in Figure 3, is cut out to allow sufficient pivoting thereof to move lug 34 away from extension 26a thereby releasing the latch (Figure 5). As best seen in Figures 4, 5 and 9, there are a pair of slots 52 and 54 formed in closure plate 46, and a spring 56 is fitted therebetween with one end 56a (Figure 5) resting on the inner side of the plate and the other end 56b fitting in a slot 34a (Figure 9) in lug 34. Accordingly, when release lever 12 is pressed to the release position indicated in Figure 5, spring 56 holds it in such position until the next closing of the case.

Referring to Figures 2, 3 and 9, casing plate 16 comprises a rear section 58, end walls 60 and 62, a bottom wall 61, a top wall 64 and an upwardly extending section 58a. Casing plate 16 also has a top flange portion 66 and a depending flange portion 68 (Figures 2 and 9) which fits over the front edge of the top of the case, resting thereagainst as shown in Figure 1. As seen in Figures 1, 2 and 9, opening 22 is formed in flange portion 66 and is positioned immediately below hook 18 (Figure 1) and above upper leg 24a of bar 24 (Figures 7, 8 and 9).

Turning to Figures 2, 3 and 9, an intermediate cover plate generally indicated at 70 has flanged side walls generally indicated at 72 preferably force fitted within walls 60, 61 and 62 of casing plate 16 to hold the various

parts in the assembled relation shown in Figures 7 and 8. More particularly, as seen in Figures 7 and 8, a lug 74 extends from the rear section 58 of casing plate 16 adjacent bar 24 to hold the bar in vertically sliding position. Referring still to Figures 7 and 9, a pair of lugs 76 extend from latch bar 26 into longitudinal slots 78 in intermediate cover plate 70. A lug 80 extends from latch member 28 into a diagonal slot 82 in cover plate 70, and this latch member is pivotally mounted in latch bar 26 by way of a circular portion 28a fitting within a hole 26b in the respective parts. A lug 84 extends from rear section 58 to support the spring 30 having a bottom section 30a resting on bottom wall 61 and a free end 30b urging bar 24 in an upward direction. Spring 32 is suitably secured to wall 62, and its free end 32a (Figures 7 and 8) preferably rests in a concavity 28b formed in the lower end of latch member 28.

Conveniently, the latch construction may be manufactured and assembled into two units by the latch manufacturer and shipped in such fashion to the luggage manufacturer where the two units can be finally assembled on the suitcase. Thus the two assembled units as made by the latch manufacturer will include as one such unit the casing plate 16 with all parts assembled therein as seen in Figure 9 with the intermediate cover plate 70 fitted into its final assembled position. The other unit so assembled at point of manufacture will, of course, include face plate 10, release lever 12 and associated parts as seen in Figure 9 but fully assembled as shown in Figures 2 and 3. Upon receipt of these parts, the luggage manufacturer first fits the cover plate and associated parts in a suitably formed cavity 86 (Figures 2 and 3) in the rear or inside surface of the case opposite an opening 88 extending through the case. Next the front piece including the face plate 10 and the release lever 12 is inserted in the opening 88 so that flange 36 rests flush against the front of the case. In such position of the parts, a pair of lugs 90 extend from closure plate 46 (Figures 4, 7 and 9) through slots 92 in cover plate 70 and slots 94 in casing plate 16; ends 90a are then bent down upon the rear surface of the casing plate to complete the assembly. By this simple operation the latching mechanism for the case is quickly installed in a permanent position without the use of screws or any other fastening elements thus effecting considerable economy in labor and materials.

Further still, it will be appreciated that casing plate 16 may be so inset in the rear or inside surface of the suitcase that a lining or cover may be placed thereover to completely conceal this portion of the latch mechanism. The front exposed portion of the latch mechanism including the face plate 10 and the release lever 12 presents a neat, simple and attractive appearance. The latch mechanism may be easily adjusted to automatically latch when the cover 20 of the suitcase is pushed into the closed position. This is accomplished by adjusting the position of the hook 18 with any suitable mechanism (not shown). Thus, the hook is located so that it will interlock with latch member 28 when the top 20 is in the closed position. Immediately beneath the keyhole 96 in release lever 12, there may be provided conventional locking mechanism mounted in the face plate 10. Such locking mechanism may be designed to lock release lever 12 upon the turning of a key against movement to the release position shown in Figure 5. Conventional locking mechanism may be utilized for this purpose and is, therefore, not shown for it forms no part of the present invention.

Not only is the latch mechanism here described simple in construction and easily assembled by the luggage manufacturer, but it may also be conveniently operated by the user. To close the suitcase it is merely necessary to push the top 20 down to the closed position. This allows hook 18 (Figures 7 and 8) to engage leg 24a of bar 24 moving the bar to the position shown in Figure 7. Such movement also moves latch bar 26 to pivot latch

member 28 as lug 80 follows along in slot 82. The result is an interfitting of the extremities 18a and 28a of hook 18 and latch member 28, respectively, as can be seen in Figure 7. To release the cover 20 it is merely necessary to press release lever 12 over the keyhole 96 to the position shown in Figure 5. This moves lug 34 out of the path of extension 26a (Figures 5 and 7) permitting spring 30 to urge the parts upwardly from the position of Figure 7 to the position of Figure 8. Spring 30 may be sufficiently strong to move the parts upwardly violently thereby producing a desirable "pop-up" effect. Preferably there may be two of these latches at opposite ends of the case. Thus, merely by exerting slight pressure on the two release bars so located, the cover 20 pops up substantially to the position shown in Figure 1 where it may be easily grasped for complete opening.

It will thus be seen that the objects set forth above, among those made apparent from the preceding description, are efficiently attained and since certain changes may be made in the above construction without departing from the scope of the invention, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

30 I claim:

1. In luggage latch construction the combination comprising a casing member adapted to be mounted substantially entirely within the thin wall of a luggage unit, an outer flange of said casing adapted to overlie an outer surface of said luggage wall in substantially flush relation thereto, a first longitudinally slidable member within said casing, a first lever arm pivotally mounted on said slidable member, and movable thereby between latching and unlatching positions, a first spring member engaged with said first lever arm and adapted to urge said slidable member longitudinally and to pivot said lever arm to an unlatched position, a releasable catch engageable with a portion of said slidable member to prevent longitudinal motion thereof whereby said first lever arm is retained immovably locked in a latching position, a manually operable externally accessible flush mounted second lever arm pivotally supported on an axis within said casing normal to but not intersecting the axis of said first lever arm, means joining said second pivotal lever arm with said releasable catch, and further spring means normally holding said second lever arm in a plane substantially parallel to and flush with said outer casing flange.

2. The combination of claim 1 including a second longitudinally slidable member having a pair of laterally extending arms encompassing said first longitudinally slidable member, and spring loading means normally urging said second slidable member in the same direction that said first spring member urges said first slidable member and said first lever arm, whereby the longitudinal motion of said first slidable member is limited by and confined within said laterally extending arms of said second slidable member.

3. In a latch construction for a luggage unit having a hinged lid with a projecting hook member depending therefrom, the combination of a casing adapted to be mounted in the top side of said luggage unit facing said hook member, a first longitudinally slidable member within said casing, a first lever arm pivotally mounted on said slidable member and movable thereby between latching and unlatching position, resilient means within said casing urging said slidable member longitudinally and pivoting said first pivotal lever arm to its unlatched position, a manually operable externally accessible second lever arm pivotally flush-mounted in said casing and

having a normally closed position and a pivotally depressed open position and catch means interconnecting said second lever arm with said first slidable member and operative when said second lever arm is in said closed position for holding said first pivotal lever arm in said latched position.

4. The combination defined in claim 3 including releasable locking means in said casing normally retaining said second pivotal lever arm in said normally closed position.

5. The combination defined in claim 3 including resilient means in said casing normally retaining said second pivotal lever arm in said normally closed position.

6. The combination defined in claim 3 including cam means adapted to guide said first pivotal lever arm between said latching and unlatching positions upon longitudinal movement of said first slidable member.

7. In a latch construction adapted to co-act with catch means on the lid of a luggage unit, the combination of an interior unit including a casing and latching mechanism adapted for mounting in the wall of said luggage unit, said latching mechanism including a longitudinally

sliding member and a latching lever pivotally mounted thereon for releasable engagement with said catch means, an exterior unit including a pivotal member adapted to be mounted on the exterior of said luggage wall opposite the interior unit, means forming an aperture in said latching mechanism adjacent said sliding member, a lug extending from said pivotal member adapted to project into said aperture and to interfit with said sliding member to hold said latching lever in engagement with said catch means, and means interconnecting said exterior and interior units to form a unitary latching structure on said luggage unit.
